Primary Examiner — Kendra Leslie Hamilton

(57) **CLAIM**

The ornamental design for a teat for liquid feeder, as shown and described.

DESCRIPTION

Teat for liquid feeder

FIG. 1.1 is a perspective view;

FIG. 1.2 is a front view;

FIG. 1.3 is a rear view;

FIG. 1.4 is a left view;

FIG. 1.5 is a right view;

FIG. 1.6 is a top view;

FIG. 1.7 is a bottom view;

FIG. 1.8 is another perspective view.

In the drawings, the broken lines depict portions of the teat for liquid feeder that form no part of the claimed design.
